United States Patent Office.

ABRAHAM MICHELBACHER, OF NEW YORK, N. Y.

Letters Patent No. 64,784, dated May 14, 1867.

IMPROVED PEAT-GATHERING MACHINE.

The Schedule referred to in these Letters Patent and making part of the same.

TO ALL WHOM IT MAY CONCERN:

Be it known that I, ABRAHAM MICHELBACHER, of the city, county, and State of New York, have invented certain new and useful improvements in Peat-Gathering Machines; and I do hereby declare that the following is a full, clear, and exact description of the same, reference being had to the accompanying drawings, making a portion of this specification, in which—

Figure 1 is a vertical longitudinal section of a peat-gathering machine constructed according to my invention.

Figure 2 is a plan view of the same.

Similar letters of reference indicate corresponding parts in both figures.

This invention consists in the combination, with a suitable carriage, of a scraper, a system of rotating buckets, and a peat receptacle, whereby the peat, in a dry pulverized or pulverulent condition, may be gathered or taken from the ground with very great ease and rapidity, and be very conveniently transported from place to place. The invention further consists in a novel means whereby the operation of the machine may be controlled at will, to cause a greater or less depth of peat to be taken from the ground as the machine is drawn along. The invention further consists in a novel means whereby the removal of the peat from the peat receptacle, in unloading the machine is very materially facilitated.

To enable others to understand the construction and operation of my invention, I will proceed to describe it with reference to the drawings.

A represents a rectangular framework, the forward end of which is furnished with a bent axle, *a*, upon each end of which is placed a supporting wheel, *B*. The opposite or rear end of this frame is constructed with downwardly-extending posts or standards, *b*, the lower ends of which are furnished with small wheels, *c*, the aforesaid frame and the wheels thereof just mentioned constituting the supporting carriage of the machine. *C* indicates a rectangular box or receptacle, which is suspended by pivots *d* in the forward end of the frame *A*, and is retained in a horizontal position when required, by means of a pin, *e*, passing through one end thereof into the adjacent end of the frame *A*, and has one of its end-boards, marked *f*, hinged at its upper edge, as shown at *a**, in fig. 1, in such manner that when desired the said end-board may be swung outward and upward to open the end of the receptacle, the said end-board being held in position to close such end, during the operation of gathering and transporting the peat, by any suitable device at the lower edge thereof. Situated midway between the inner end of the receptacle *C* and the rear end of the frame *A*, is a transverse shaft, *D*, which is furnished at one end with a balance-wheel, *g*, and at the other with a pinion, *h*, which is connected by an intermediate spur-wheel, *i*, with a gear-wheel, *k*, secured to one of the supporting wheels *B*. This shaft *D* is furnished with any requisite number of radial arms, *m*, to the outer ends of which are secured the transverse buckets *E*, the shape of which is indicated more fully in fig. 1, and which are arranged in a series concentric with the shaft *D*, as shown in the said figure. The curved scraper *F* is situated transversely at the rear end of the frame *A*, and is secured to the lower ends of the upwardly-extending handles *n*, and pivoted to the sides of the frame *A* by lateral pivots passed through the aforesaid handles, as shown at *b**. This scraper is extended forward, so that its front edge is brought below the rotating buckets *E*, and nearly or quite underneath the shaft *D* thereof.

The machine being drawn along by horses or other draught animals, by means of a suitable tongue or shaft attached to its forward end *A**, the person using the same grasps the handles *n*, and, by elevating the said handles, forces down the forward or cutting edge of the scraper into the peat upon the ground, to a greater or less depth, as may be required; the said peat having been first brought into a more or less dry and pulverized or comminuted condition. The peat then passes upward upon the curved or inclined surface of the said scraper. At the same time the series of buckets *E* being rotated in the direction of the arrow by the motion of that wheel *B*, to which the spur-wheel *k* is secured, the said buckets, as they pass upward over the said scraper, are filled with the peat collected thereon, and carry the same upward and over, until, their position being reversed, as they pass downward in front of the shaft *D*, the peat is thrown or dropped therefrom into the box or receptacle *C*, the peat, as the machine moves forward, being thus conveyed from the scraper to the receptacle, until the latter is filled, which being done, the handles *n* are depressed so as to bring the scraper above the surface, and the machine is then drawn to the place where it is desired to deposit the peat, whereupon the pin *e* is removed, and the receptacle *C* is tilted upon its sustaining pivots *d*, so as to bring nearer to the ground that end thereof which is furnished with the hinged end-board *f*. The said board is then swung outward and upward to open

such end of the receptacle, thus allowing the contents of such receptacle to fall freely out therefrom. By these means the peat may be gathered from the ground at a very slight expense, and readily transported to the desired place of deposit.

What I claim as my invention, and desire to secure by Letters Patent, is—

1. The combination of the scraper F, the rotating buckets E, and the receptacle C, with a suitable carriage, substantially as and for the purpose specified.
2. The scraper F, pivoted in rear of the rotating buckets E, and furnished with handles *n*, whereby the said scraper may be made to operate at a greater or less depth, substantially as herein set forth.
3. The receptacle C, suspended on pivots in front of the rotating buckets E, and constructed with an end-board, *f*, hinged at its upper edge, substantially as and for the purpose specified.

A. MICHELBACHER.
